Patented Nov. 25, 1913.

UNITED STATES PATENT OFFICE.

KARL JOHAN OHLSON, OF CHICAGO, ILLINOIS.

LAMP-SUPPORT.

1,079,715.

Specification of Letters Patent. Patented Nov. 25, 1913.

Application filed November 4, 1912. Serial No. 729,284.

To all whom it may concern:

Be it known that I, KARL J. OHLSON, a subject of the King of Sweden, and a resident of Chicago, Cook county, Illinois, have 5 invented certain new and useful Improvements in Lamp-Supports, of which the following is a specification.

My invention relates to supports for lamps and the like and has special reference to 10 electric light lamp supports.

The object of the invention is to provide an adjustable arm of simple and inexpensive construction that affords the rigidity necessary to prevent disturbing vibrations of the 15 lamp and yet provides all the necessary adjustments longitudinally from as well as angularly to the wall or base of said support.

With the above named object in view my invention consists in the novel construction, 20 combination and arrangement of parts hereinafter described in detail, illustrated in the accompanying drawing and incorporated in the appended claims.

In the drawing—Figure 1 is a section on 25 line 1—1 of Fig. 2. Fig. 2 is a side view of the arm, bracket or lamp support embodying my invention, the base-plate being shown in section. Fig. 3 is a top plan view of same. Fig. 4 is an enlarged detail view broken 30 away, showing the method of holding the longitudinally adjustable extension-rod. Fig. 5 is a similar view showing a modification. Fig. 6 is a section taken on line 6—6 of Fig. 2, on an enlarged scale. Fig. 7 is a 35 section taken on line 7—7 of Fig. 2 and enlarged.

In the several views 2 represents a triangular base-plate, which may be conveniently made out of wood. Same is fastened 40 by screws 3, 3 to a wall or other suitable stationary object. Hinged on screw-eyes, or other suitable joints, 4 and 5 are a series of rods 6, 7 and 8 which are curved as shown in Figs. 2 and 3, to meet or form a bundle or 45 cluster with a rod or pole 9 in the periphery of which are grooves 10, 11 and 12 which extend the full length of said rod or pole and receive the rods 6, 7, and 8, respectively. The bundle thus formed of rods 6, 7, 8, and 50 9 is clamped together at the point where said rods cluster, by a band 13 having ends 14 and 15 engaged by a bolt and butter-fly nut 16 whereby said band may be contracted or clamped upon the cluster of rods. A tight 55 clamping will make the rods substantially immovable longitudinally relative to each

other while a moderate contraction of the said band will permit the rods 6, 7, and 8 to slide or move longitudinally relative to each other in their channels or grooves 10, 11 and 12. The center rod 9 of the cluster is movable longitudinally relative to the other three rods supported on said center rod to lengthen or project the reach of the lamp-support or arm composed of said four rods. 60 The rod 9 may be thus adjusted to lengthen or shorten the arm to the extent of the distance between the clamp 13 and the base-board 2. Provision is made for additional lengthening of the arm in the form of an 65 extension rod 17 mounted on eyes 18 and 19, or screw-eyes screwed into the rod 9 as shown. The forward end of the extension rod 17 has secured therein an open screw-eye 20 adapted to receive the cord or other suitable part of an electric lamp. The rod 9 is similarly equipped with a hook or eye 21 for the same purpose. 70

The principal support for an electric light bulb is near the end of the rod 9, and consists of a wire or metal rod having a straight shank portion 22 and a curved portion 23, which forms an arc slightly larger than a half circle and adapted to engage the socket portion 24 of an electric light bulb and hold 80 it with a spring-grip. The part 23 will therefore be made with sufficient flexibility to grip the neck of the bulb with a moderate frictional engagement. The shank 22 is held so that it may be adjusted rotatably on 85 and angularly about its axis by means of a bolt 25 having an elongated or round hole 90 therein for the shank 22. A washer 27 is interposed between the shank 22 and pole or rod 9 and this washer is provided with a 95 hole 28 large enough to permit the head 29 of the bolt to pass through it, thus clamping the shank 22 between the washer and the head. The head of the bolt is drawn against the shank 22 by means of a thumb-nut 30 on 100 the threaded end 31 of the bolt. Between said nut and the rod is interposed another washer 32.

In Fig. 6 the bolt for tightening the clamp 13 is shown with a winged head 16 engaging 105 the end or lug 14, while the threaded portion 33 of the bolt has threaded engagement with the lug 15. The extension rod 17 is shown in Fig. 3 as held by a bolt 34 having threaded engagement with the rod 9 and 110 bearing against the rod 17. The bolt is turned by means of a winged head 35.

- In Figs. 4 and 5 modifications are shown. In Fig. 4 the bolt 34 bears against an arched spring 36 interposed between the bolt and the rod 17 to give a yielding engagement. 5 In Fig. 5 a spring 37 held by screws 38 is interposed between the rods 9 and 17 and is alone relied upon for holding the rods in the positions in which they are adjusted on each other longitudinally.
- 10 All of the parts may be adjusted to the weight of the arm as a whole to permit the different adjustments of lengthening or shortening the arm by means of the rods 9 and 17 and swinging the arm in any desired direction, so that the frictional engagement will be sufficient to support the rods in the positions they are placed and yet permit their relative sliding movement without loosening the clamps.
- 15 20 As the above-described construction involves principally the use of wooden strips, rounds or rods, although adapted for metal rods as well, the invention may be manufactured at a comparatively small cost. The spread of the rods to the corners of the base-board gives the arm a truss-support in whatever position it is placed, and the longitudinal adjustment of the rod 9 relative to the rods 6, 7 and 8 affords a range of adjustment as to reach which is ample for all ordinary purposes without resorting to the use of the rod 17. Where it is desirable to place the arm high and let the lamp drop some distance below the end thereof the hooks or eyes in the end of the arm will support the lamp cord conveniently by simply winding said cord about the hook one turn.
- 25 30 35 Having thus described my invention, I

claim as new and desire to secure by Letters Patent—

1. The combination with a stationary support, of an arm consisting of a center rod and a plurality of rods relatively slidable on said center rod and forming therewith a bundle of rods or spindles held together by frictional engagement, said rods being spread apart each separately jointed to said support for movement angularly relative thereto, means for clamping said rods together against movement longitudinally relative to each other, and means for clamping an electric light bulb on the free end of said arm. 40
2. The combination with a base-board, of means for fastening said board to a wall or the like; a series of rods or spindles movably jointed to the corners of said base board, a clamp clamping the major portion of said rods together, a rod 9 to which said rods are clamped, said rod 9 having grooves 45 therein to receive said rods, an extension rod mounted on said rod 9, means for adjustably clamping said rod 9 and extension rod together, means upon said rod 9 for clamping an electric light bulb removably thereto, 50 means in addition thereto on said rod 9 for supporting an electric light bulb cord, and similar means on said extension rod. 55

In testimony whereof I have hereunto set my hand in the presence of two subscribing witnesses. 60

KARL JOHAN OHLSON.
